UNITED STATES PATENT OFFICE.

ABRAM MOLL, OF WILLIAMSON, NEW YORK.

PLOW ATTACHMENT.

1,280,271.

Specification of Letters Patent.

Patented Oct. 1, 1918.

Application filed October 19, 1917. Serial No. 197,479.

To all whom it may concern:

Be it known that I, ABRAM MOLL, a citizen of the United States, residing at Williamson, in the county of Wayne and State of New York, have invented certain new and useful Improvements in Plow Attachments, of which the following is a specification.

This invention relates to plow attachments and more particularly to the standard used in connection with the gage wheel.

The principal object of this invention is to provide a simple and effective device whereby the standard may be raised or lowered relatively to the plow beam to regulate the depth of the furrow to be plowed.

Another object of this invention is to provide a locking means for the fastening pin used for maintaining the standard in its adjusted position.

With these and other objects in view the invention consists in the construction, combination and arrangement of parts, as will be hereinafter fully described and claimed.

Reference is to be had to the accompanying drawings forming part of this specification, in which like reference characters indicate corresponding parts throughout the several views, and in which

Figure 1 is a view of a plow showing the attachment in operative position,

Fig. 2 is a fragmental sectional view of the plow beam showing the manner of adjusting the standard, and

Fig. 3 is a sectional view on the line 3—3 of Fig. 1.

Referring more particularly to the drawings, 5 indicates a plow beam carrying a clevis 6, 7 a plow share and 8 plow handles which are connected to the plow beam by the 40 brace member 9, all of these parts being of the usual construction, with the exception of the plow beam 5 which has an opening passing therethrough to accommodate the standard 10 and mechanism for holding it in 45 a desired position relative to the beam.

The standard 10 is substantially rectangular in cross section and is provided on one edge with a plurality of teeth 11 forming a rack bar. The gage wheel 12 is carried by 50 one end of the standard. The side of the standard 10 opposite the teeth rests in engagement with the wall 13 of the opening which prevents the standard from being moved out of vertical alinement should the

caster wheel come into contact with an obstacle in its path.

A wheel 14 provided with teeth or cogs 15 is mounted on the axle 16 passing through the beam 5 and which is held in position therein by the nut 17 and pin 18 passing through the axle 16. It will thus be seen that the axle may be easily removed to replace either it or the wheel should either become damaged or otherwise affected. The wheel has a plurality of openings 18 arranged at equal distant points around its circumference through which the securing pin 19 is adapted to pass to hold the wheel in a fixed position as will be more fully described hereinafter. The teeth 15 of the 70 wheel engage with the teeth 11 of the standard and when the wheel is fixed in any desired position the standard will be prevented from movement in either an upward or downward direction.

The pin 19 which is used for securing the wheel has one end reduced as at 20, which is more clearly seen in Fig. 3, and is provided with a knob 21, while the other end of the pin is shaped to form an eye 22 to which may be fastened a chain to hold the pin connected with the beam preventing loss thereof. The eye also provides a means of gripping the pin to withdraw it from position.

Below the opening through the beam in which the axle 16 is positioned there is a second opening 23, and on the opposite side of the beam and in alinement with this opening there is a chamber 24 in which is secured a spring gripping member 25 which is adapted to receive the knob 21 of the pin securely holding it therein. The openings 18 register in turn with the opening 23 and the chamber 25 making a clear passage way for the pin 23, and the openings 18 and 23 are substantially of the same diameter while the chamber 25 is somewhat larger in diameter so as to allow the pin to be entered therein without difficulty.

In operation the standard 10 is adjusted so as to bring the gage wheel in proper position to permit the plow 7 to cut a furrow of the desired depth, which will bring one of the openings 18 in the wheel into alinement with the chamber 25 and its alined opening 23, by virtue of the teeth meshing with the teeth of the standard, when the pin 23 may be passed therethrough and forced into the

spring arms of the gripping member 25 which will securely hold it from accidental displacement. Of course, if one of the openings 18 should not exactly register with the opening 23 and chamber 25, the standard may be moved in order to bring this about, the movement thereof being of such an extent, owing to the number of openings in the wheel 15, that no appreciable difference will be observed in the depth of the furrow.

Various minor changes may be resorted to in the construction, combination and arrangement of parts without sacrificing any of the principles or departing from the spirit 15 of the invention as indicated in the appended claims.

Having fully described my invention, what I claim as new and novel is:

1. The combination with a plow beam 20 having an opening therethrough, a chamber in communication with the opening, and a second opening in alignment with the chamber, of a standard movable through the first opening, a rack bar formed on the standard, 25 a rotary means secured in the said first opening engaging with the rack bar, and means passing through the second opening and received in the chamber for holding the rotary means against movement.
2. The combination with a plow beam 30 having a vertical opening therethrough, a plurality of transverse openings, one of which passes part way through the beam and a chamber in alignment with the open-

ing passing part way through the beam, of a standard, movable in the vertical opening, a rack formed on said standard, a tooth wheel rotatable in the vertical opening and engaging with the rack bar, said wheel having a plurality of openings alined at times with the said chamber and the opening passing partially through the beam, and a means 40 passing through the alined openings and received in the chamber for securing the tooth wheel against rotation.

3. The combination with a plow beam having a vertical opening therethrough, a transverse passage way through the beam, a second opening passing partially through the beam, a chamber communicating with the vertical opening and in alignment with the second opening, and a gripping means mounted in the chamber, of a standard movably mounted in the vertical opening, a rack bar formed on the standard, a tooth wheel 50 mounted in the vertical opening and engaging with the rack bar, the wheel having a plurality of openings alined with the chamber and its alined opening, and means having a knob thereon passing through the alined openings and held in the chamber by the gripping means.

In testimony whereof I affix my signature in presence of two witnesses.

ABRAM MOLL.
